UNITED STATES PATENT OFFICE.

ANDREW J. WOOD, OF BAKERSFIELD, CALIFORNIA.

TRAIN-ORDER DELIVERER.

1,300,911.

Specification of Letters Patent. Patented Apr. 15, 1919.

Application filed February 21, 1917. Serial No. 150,102.

To all whom it may concern:

Be it known that I, ANDREW J. WOOD, a citizen of the United States, and resident of Bakersfield, in the county of Kern and

5 State of California, have invented certain new and useful Improvements in Train-Order Deliverers, of which the following is a specification.

This invention relates to railway applications and has more especial reference to an improved train order deliverer.

The dominant object of the invention is to provide novel means whereby a train order may be efficiently delivered to the crew of a 15 moving train, thereby, eliminating the necessity of bringing the train to a full stop before the receiving of the order.

Another object of the invention is to provide an improved order holding means, 20 whereby, when one order is removed therefrom a second will be instantly and automatically moved into delivering position.

A further object of the invention is to provide means for yieldably supporting the 25 order delivering means, thus, allowing the same to be abruptly removed without fracturing the same or tearing or mutilating the order.

Other and further improvements and 30 novel details in the construction and arrangement of parts will be appreciated from the description to follow, which, for a clear understanding of the invention, should be considered in connection with the accompanying drawing, forming a part hereof, and wherein the preferred embodiment of 35 the invention is shown for the purpose of illustration.

In the drawing:

40 Figure 1 is a perspective of my improved train order holding and delivering device, and

Fig. 2 is a vertical longitudinal section therethrough.

45 With more particular reference to the drawing, wherein like reference numerals refer to corresponding parts throughout the several views, a supporting post 1 is provided and has arranged upon the upper flat-tened portion thereof a base plate 2, the base plate in turn receiving thereupon the annular stand portion 3 of a vertically disposed spindle 4, the upper extremity of the said spindle being screw-threaded as at 5, the 50 purpose of which will be subsequently apparent. An annular anti-frictional bear-

ing race-way is formed within the upper face of the stand 3 and receives therein a plurality of bearings, generally indicated by the numeral 6.

With a view toward providing means whereby the various train orders may be held in position in order to be grasped by certain of the crew of the moving train, there is provided a rotatable supporting 60 means designated in its entirety by the numeral 7 and comprising a hub portion 8 adapted to be loosely mounted upon the vertically disposed spindle 4, carrying thereon a plurality of radiating sockets 9, which 65 sockets receive therein the train order delivering and holding means. As will be noted, one portion of the hub 8 is substantially cylindrical and thus affords an efficient winding drum, the purpose of which 70 will be hereinafter more fully described. To secure the hub portion 8 of the support 7 in position upon the vertically disposed spindle 4, a locking nut 10 is turned into engagement with the screw-threaded portion 5 75 of the spindle. To eliminate friction to the greatest possible extent, a bearing race-way is formed within the lower face of the hub portion 8, preferably, in direct alignment with the race-way as formed within the 80 annular stand 3 and as will be obvious, receives the upper portions of the bearings 6 85 therein.

To one side of the post 1, a bar 11 is secured and has its upper extremity bifurcated whereby a guide pulley 12 may be rotatably mounted therein. Directly beneath the bar 11, a bracket 13 is arranged and has pivotally mounted between the side portions thereof an arm 14, which arm has 90 slidably arranged thereupon a weighted element 15, the said weighted element being secured in its various adjusted positions through the medium of the set screw 16 turned into engagement therewith and 100 adapted to bind at times upon the adjacent face of the said arm 14. A cable 17 is secured at one end thereof to the arm 14 and passes upwardly over the guide pulley 12 about the winding drum portion of the hub 8. Thus, it will be understood that when a portion of the cable 17 is coiled about the winding drum of the hub 8 the weighted arm 14 will be drawn upwardly and as a 105 consequence, the cable 17 will be placed 110 under tension.

A right angularly formed arm 18 is se-

cured to the plate 2, preferably, at a point opposite to the mounting of the bar 11 and has the vertically disposed portion thereof arranged in proximity of the outer 5 extremities of the various socket members 9 carried by the rotatable support 7.

A train order holding and delivering rod 19 is provided and has the outer extremity thereof looped as at 20, whereby a train order, such as designated by the numeral 21 may be readily engaged therewith, the loop being so positioned as to permit the same to be readily grasped by certain members of the crew of the passing train. Obviously, by placing the rod 19 within certain of the various sockets 9, the same will be brought into engagement with the vertically disposed portion of the arm 18 by reason of the cable 17 and the weighted arm 14 which is engaged therewith. Thus, when the loop of the rod 19 is grasped by the member of the train crew to remove the same from its respective socket 9, the support 7 will not be rotated until the rod 25 has been entirely removed from the said socket 9. At this time, the support 7 will be then rotated until the cable 17 has been entirely uncoiled from the winding drum of the hub portion 8. By so engaging the 30 order holding and delivering rod 19 with the various sockets 9 of the support 7, it is to be appreciated that the same will be permitted to yield to the onrush of the train and as a consequence, fracturing of the 35 rod and mutilating of the train order is eliminated. It may be here noted, that a plurality of train order delivering and holding rods 19 may be engaged with the various sockets 9 of the support 7 and when 40 such is the case, upon the removal of one of the rods 19 from its respective socket, the support 7 will be permitted to rotate until the next or following rod is engaged.

with the vertically disposed portion of the arm 18, whereat, it will be maintained in 45 delivering position. When the second order has been removed, the third rod will be brought into engagement with the arm 18 and so on until the entire number of the same have been removed from the various 50 sockets 9.

While I have herein illustrated and described with a considerable degree of particularity constructional details of the device embodying my invention, it is to be 55 understood that the invention is not limited to the particular form and arrangement of the several parts which may be modified within a wide range without departing from the essence of the invention, the construction shown and the description based thereon being intended to be taken in an 60 illustrative rather than a limiting sense.

I claim:

A train order holder and delivering device including a base, a bearing table on said base, a horizontally arranged rotatable order holding and delivering member mounted on said table comprising a body portion having radially disposed tubular extensions 70 and a vertical winding drum, said body, extensions and drum being formed in a single piece, a flexible connection engaged at one end with said winding drum, a weighted arm pivoted to the base and engaged with 75 the remaining end of said flexible connection, order holding and delivering rods receivable in the tubular extension, and an upright stop arranged in proximity to the rotatable order holding and delivering 80 means adapted to be engaged with one of said rods for maintaining the same in a predetermined position to be engaged.

In testimony whereof, I affix my signature hereto.

ANDREW J. WOOD.
